UNITED STATES PATENT OFFICE.

CHARLES H. SERGEANT, OF NEW YORK, N. Y.

MINING-COLUMN.

SPECIFICATION forming part of Letters Patent No. 444,140, dated January 6, 1891.

Application filed July 17, 1890. Serial No. 359,064. (No model.)

To all whom it may concern:

Be it known that I, CHARLES H. SERGEANT, of the city and county of New York, in the State of New York, have invented a new and 5 useful Improvement in Mining-Columns, of which the following is a specification.

My invention relates to an improvement in mining-columns in which a pair of standards are united by two parts—upper and lower cross-heads—which may be readily removed and adjusted for the purpose of increasing or diminishing to a considerable extent the length of the column.

The object is to provide simple and effective means for securing the upper end of the column in engagement with walls of varying angles, and at the same time transmit the thrust of the engagement of the column of the wall to the cross-head rather than to the pivotal connection of the engaging fork with the cross-head, and in general to provide a column which may be firmly adjusted and readily removed, and it may be readily adapted to a great variety of positions.

25 A practical embodiment of my invention is represented in the accompanying drawings, in which—

Figure 1 is a view of the column in side elevation, one-half of the upper and lower cross-head being removed. Fig. 2 is a transverse section through the line *x* *x* of Fig. 1, and Fig. 3 is a vertical transverse section through line *y* *y* of Fig. 1.

A represents the standards, which may be 35 conveniently formed of piping—gas-piping, for example—and may be prepared in suitable lengths and kept conveniently at hand, so as to accommodate the length of column approximately to the length of the distance of the 40 walls with which its opposite ends are to be engaged. The opposite ends of the standards A are received in sockets *b*, formed in the ends of the sectional upper and lower cross-heads B and B'. Each of the cross-heads B and B' is made in two similar half-sections, bolted together and drawn into close contact with the standards A by means of screw-bolts C, provided with nuts *c*. Between the half-sections of the upper cross-head B the engaging fork D is centrally pivoted upon a bolt *d*, its branches *d'* projecting outwardly and upwardly from the central portion and

being provided at their ends with sharp edges *d'*, for the purpose of biting into the hard wall of mineral. The engaging fork D is allowed considerable play upon the pivotal bolt *d*, and its lower central portion is rounded, as shown at *d''*, and rests in close proximity to a curve-faced bearing-lug *b* on the cross-head B, so that when pressure is exerted to throw 55 the edge *d'* into contact with the wall of mineral the thrust will be received upon the concave face of the lug *b'* before the fork D engages closely with the pivotal bolt *d*. This provides against any liability of springing or 60 breaking the bolt *d* and renders it feasible to employ a much lighter bolt than where the weight is thrust upon the bolt itself.

Between the half-sections of the lower cross-head B' an internally-screw-threaded sleeve 70 E is secured, the opposite ends *e* of said sleeve being enlarged and overlapping the upper and lower edges of the half-sections of the cross-head, as clearly shown in Fig. 1, whereby the said sleeve is prevented from vertical movement when the half-sections of the cross-head are bolted together.

Within the sleeve E a heavy screw F is seated, and is provided with a sharp point *f* for engagement with the wall of mineral and 80 with a head *f'*, provided with sockets or perforations *f''* for the reception of a lever for the purpose of rotating the screw, and thereby forcing the sharp edges of the fork B and the point *f* of the screw into engagement with the 85 wall of mineral.

Whenever it is desired to adjust the column to a length greater than what can readily be provided for by the screw F, the bolt C may be loosened, the standards A removed, 90 and a set of longer standards inserted in their places.

The column which I have herein shown and described is particularly well adapted for use in connection with an auger-support—such, 95 for example, as that shown and described in an application executed and filed by me of even date herewith.

What I claim as my invention is—

1. The combination, with the standards and 100 the cross-heads for securing the standards together, one of the cross-heads being formed in separable sections, of an engaging device pivotally secured between the separable sec-

tions of the cross-head, and a bearing upon the said cross-head with which the engaging device contacts when under strain before it contacts with its pivotal connection, the said sections of the cross-head forming a guide for the engaging device intermediate of its bearing and engaging ends, and means for adjusting the column, substantially as set forth.

2. The combination, with an upper and lower cross-head, each formed in half-sections and provided with sockets at their opposite ends, of standards adapted to enter said sockets for increasing or diminishing the length of the column, and engaging devices at the upper and lower ends of the column, substantially as set forth.

3. The combination, with a pair of standards, an upper sectional cross-head engaging the upper ends of the section, and a lower sectional cross-head engaging the lower ends of the standards, of an engaging fork pivotally secured between the sections of the upper cross-head and an engaging screw having a threaded connection with a sleeve, the latter being engaged between the sections of the lower cross-head, substantially as set forth.

CHARLES H. SERGEANT.
